UNITED STATES PATENT OFFICE.

JACOB B. WENZEL, OF BLOOM, COLORADO.

METHOD OF AND MACHINE FOR MAKING PACKING RINGS.

Application filed August 28, 1920. Serial No. 404,824.

To all whom it may concern:

Be it known that I, JACOB B. WENZEL, a citizen of the United States, and a resident of Bloom, in the county of Otero and State 5 of Colorado, have invented new and useful Improvements in Methods of and Machines for Making Packing Rings, of which the following is a specification.

This invention relates to a method of and 10 machine for densifying the metal in a piston ring to produce the required resiliency in the ring so that the ring will exert a uniform radial pressure on the walls of a cylinder when the ring is in operative position 15 on a piston.

Heretofore in the densification of the metal in piston rings to produce the necessary resiliency in the ring by forming indentations or corrugations in one of the surfaces thereof, the said indentations have 20 usually been formed by hammering. This method requires complicated machinery and it has been found difficult to accurately form and space the indentations due to the unreliability of the machinery used for hammering and rotating the ring.

The objects of my invention are to overcome the difficulties incident to the use of the modern hammering methods and machines by densifying the metal in a piston ring by an improved method of rolling; to provide an improved method consisting in rolling indentations into the surface of a piston ring under yielding pressure to prevent injury to a ring of uneven thickness; to obtain a method of densifying the metal in a piston ring consisting in a combined rolling and hammering operation; to provide an improved machine for rolling piston 30 rings to densify the metal therein and produce the required resiliency; to utilize for this purpose an anvil or ring support and a rolling die between which the piston ring is inserted to be operated upon with means 35 to accommodate slight irregularities in the surface of the ring to prevent breaking of the ring during the rolling operation as it passes under the die; to utilize for this purpose a yielding relation between the ring supporting anvil and the rolling die; to provide means for adjusting the pressure of the rolling die upon the ring to vary the densification of the piston rings; to provide improved automatic means for stopping the 40 rolling apparatus as the operation upon a piston ring is completed; to provide means 45

for hammering the ring simultaneously with the rolling thereof; to utilize an arcuate rotating die which is formed on its working face with points or projections to form corresponding indentations in a piston ring with means for simultaneously rotating said die and exerting successive blows thereon to roll and hammer indentations into the ring, and to obtain other results and advantages 60 as may be brought out by the following description.

Referring to the accompanying drawings, in which like numerals of reference indicate the same parts throughout the several views, 70

Figure 1 is a front elevation of a machine embodying my invention;

Figure 2 is an elevation of the left side of the machine, as viewed from the front;

Figure 3 is an elevation of the opposite 75 side of the machine, portions thereof being broken away and shown in section;

Figure 4 is a top plan view of the machine;

Figure 5 is a vertical sectional view taken 80 on the line 5—5 of Fig. 3, and illustrating the clutch and stop mechanism;

Figure 6 is a detached top plan view of the piston ring support or anvil, and

Figure 7 is a vertical sectional view 85 through the same.

In the specific embodiment of the invention illustrated by the drawings, the numeral 1 designates the bed of the machine which is shown as supported upon suitable 90 legs 2. A shaft bearing head 3 is mounted at the rear end of the bed, the said bearing head being substantially of an inverted U-shaped formation and comprising an overhanging extension 4 which is spaced a substantial distance from the main portion of the head 3. A horizontal drive shaft 5 is journaled within the said bearing head 3 and extension 4 at one side of the machine, the said shaft being geared by means of the 95 pinion 6 and gear wheel 7 to a counter shaft 8 arranged at the opposite side of the machine and substantially parallel with the drive shaft 5. The drive shaft 5 may be driven in any suitable manner as by the 100 belt and pulley 27 shown in Figures 1 and 2.

The counter shaft 8 projects a substantial distance forwardly of the extension 4 of the shaft bearing head and is formed at its forward end with a die supporting arbor 10 110 upon which is fixed a die 11 the working surface 12 of which is of a radius slightly

smaller than the radius of the piston ring to be operated upon, the said working surface being formed with suitable projections 13 which are adapted to form corresponding 5 indentations in the surface of the piston ring for the purpose of densifying the metal therein to produce the necessary resiliency. The working surface 12 of the die member 11 is substantially concentric with the shaft 10 8 and extends for only a portion of the periphery of the die member while the opposite side of the die member is cut away at 11^a. The die member 11 may be secured to the arbor in any suitable manner as by 15 means of the spacing sleeve 14 and the clamping nut 15, the die member being secured between the said sleeve and nut. A bearing bracket 16 projects forwardly from the extension bearing 4 and has at its outer 20 end a half bearing 17 which engages the upper half of the forward part of the counter shaft 8.

A piston ring support or anvil 18 is arranged beneath the die 11 to support the 25 piston ring while it is being operated upon by the said die. This anvil may be of any suitable construction, but in the present instance it is shown as comprising a casing having an annular recess 19 in the upper 30 face thereof in which are mounted the ball bearings 20. The said recess 19 is closed by a substantially horizontal anvil ring 21 which is rotatably mounted on the anvil 18 by means of the screw 22, the said anvil ring 35 resting upon the balls 20. The upper surface of the anvil ring 21 at its edge is cut away as at 23 inwardly of the ring a distance substantially equal to the width of the piston ring to be operated upon so that a 40 vertical shoulder 24 is provided to form a guide for the piston ring upon the anvil ring 21. An adjustable slide 25 is mounted on the anvil 18 to cooperate with the shoulder 24 on the anvil ring to maintain the 45 piston ring in proper relation to the die 11 and prevent the piston ring from moving laterally from beneath the said die member. At the side of the anvil opposite the slide 25 is secured a keeper plate 26 which overlaps 50 the anvil ring 21 as indicated in Figures 6 and 7 so as to prevent the said anvil ring from tilting when pressure is exerted upon the ring by the die member 11. In operation the piston ring is set upon the anvil 55 ring 21 between the shoulder 24 and the slide 25 as indicated by dotted lines in Figure 7 and dot and dash line in Figure 1, the piston ring being so positioned that the projections 13 on the die member when the 60 same is rotated will engage the ring at the proper point to ensure densification of the proper portion of the piston ring. As the die member 11 is rotated the projections 13 will successively engage the surface of the 65 piston ring, and the piston ring will thereby

be rotated by the rotation of the die member, the anvil ring 21 rotating beneath the piston ring upon the balls 20 through the frictional engagement of the piston ring with the anvil ring. The piston ring is thus 70 smoothly and evenly rotated and successive portions thereof operated upon by the die member in order to accurately and uniformly densify the metal in the piston ring.

It is desirable to stop the rotation of the 75 die member 11 after the operation upon the piston ring has been completed in order to prevent repetition of the operation which would injure the ring, and also to enable the ring to be removed from the anvil. 80 When the die member is in its normal inoperative position the working surface 12 thereof is at the upper side of the shaft 8 and the cut away portion 11^a thus provides a substantial clearance between the anvil 85 and the die member for the purpose of inserting a ring between the die member and anvil and removing the same therefrom. For so stopping rotation of the die member, a belt pulley 27 is mounted to rotate upon the drive shaft 5, the said pulley being provided with a friction clutch surface 28 to cooperate with a clutch disk 29 fast upon the drive shaft 5, the said pulley and clutch disk being normally separated by the spring 90 30. A clutch lever 31 is pivotally mounted intermediate its ends as at 32 upon the inner side of the extension shaft bearing 4, the outer end of said clutch lever engaging the pulley 27 and being connected by a link 100 33 to one end of a translating lever 34 pivotally mounted between its ends at 35 upon the extension bearing 4, the opposite end of said translating lever being connected to a clutch rod 36 having a handle portion 37 105 arranged at the front of the machine. The inner end of the clutch lever 31 is provided with an angularly projecting head 38 which normally engages a notch 39 in the periphery of a disk 40 fast upon the counter shaft 110 8, the said head 38 of the clutch lever thus locking the counter shaft 8 against rotation. To start the machine the clutch rod 36 is pulled forwardly which forces the pulley 27 into engagement with the friction disk 115 29 against the action of the spring 30, and simultaneously removes the head 38 of the clutch lever 31 from the slot 39 in the disk 40. The drive shaft 5 and counter shaft 8 are thus started in rotation, and when the clutch rod 36 is released, the spring 30 tends to return the clutch lever 31 to its original 120 position. However, the full return movement of the clutch lever is prevented by the engagement of the head 38 thereof with the side face of the disk 40 until a complete revolution of the counter shaft 8 has been accomplished, after which the spring 30 will force the head 38 of the clutch lever 31 into the notch 39 of the disk 40 to stop rotation 125 130

of the counter shaft 8 and simultaneously disengage the pulley 27 from the clutch disk 29. For the purpose of instantaneously stopping the rotation of the drive shaft 5 to overcome the momentum thereof which would tend to strain the mechanism or strip the gears, a brake member 41 is slidably mounted in the shaft bearing head 3 and is adapted to be forced into engagement with the clutch disk 29 at the end of one rotation of the counter shaft 8 by means of a brake operating arm 42 secured to the said shaft 8, the said brake operating arm projecting beyond the periphery of the gear wheel 7 as shown in Figure 4 and having its outer end inclined outwardly so as to engage and slip over the projecting end of the brake rod 43 and force the brake 41 against the clutch disk 29. A spring 44 is preferably provided for normally holding the brake 41 from engagement with the clutch disk 29 and maintaining the outer end of the brake rod 43 in the path of the brake operating arm 42.

In the manufacture of piston rings it often occurs that some of the rings are of varying thicknesses at different portions of their lengths due to inaccuracy in manufacture, and were the anvil 18 rigidly fixed with respect to the die member 11 the ring being operated upon would be cracked or broken when one of these irregularities on the piston ring was encountered by the die member 11. To overcome this difficulty the anvil 18 is shown as yieldingly mounted with respect to the die member 11 so that when an irregularity in the piston ring passes beneath the die member 11 the anvil will yield away from the roll to allow the irregularity to pass without breaking the ring. Any suitable construction may be employed, but in the present instance the anvil is shown as provided with a polygonal post 45 which is vertically slidable through a supporting bracket 46 mounted on the bed 1 of the machine, the polygonal formation of the post 45 preventing rotation of the anvil. A counter weight lever 47 has one end thereof pivotally connected to the lower end of the post 45, the said lever being fulcrumed at an intermediate point in its length upon the fulcrum link 48 pivotally connected to a lug 49 projecting from the bracket 46. A counter weight 50 is adjustably mounted upon the opposite end of the said counter weight lever 47, and it will thus be obvious that when a predetermined pressure is exerted by the die member 11 upon the anvil 18 the anvil will be forced downwardly against the action of the counter weight 50 so as to allow any irregularity on the piston ring to pass the die member. The fulcrum link 48 will allow a slight longitudinal movement of the lever 47 to compensate for the vertical movement of the anvil 45 to prevent binding of the post 45 of the bracket 46, and by adjusting the counter weight 50 longitudinally of the lever 47 the amount of pressure exerted upon the piston ring can be varied. This pressure is preferably just sufficient to produce the friction between the ring and die member required for rotation of the ring by the die, but it will be understood that said pressure may be adjusted for the purpose of rolling the indentations into the ring under pressure. To prevent the counter weight 50 from forcing the anvil upwardly against the counter shaft 8 an adjustable stop screw 51 may be secured in the bed 1 beneath the lever 47 so as to limit the downward movement of the counter weight 50. By means of this adjustable stop screw 51 the distance between the die member 11 and the anvil 18 can also be adjusted to accommodate various thicknesses of piston rings.

My invention also contemplates the hammering of the indentations into the piston ring simultaneously with the rolling thereof, and I have illustrated in the drawings one possible apparatus for accomplishing this result, although other constructions might be utilized. As shown in the drawings, a pair of ratchet wheels 52 are mounted fast upon the drive shaft 5, the teeth of the said ratchet wheels being arranged in staggered relation as shown by Figure 1 of the drawings. A hammer lever 53 for each of the ratchet wheels 52 is pivotally mounted at 54 upon the bracket 46, the said hammer levers comprising substantially horizontal arms 55 upon which are mounted lugs 56 engaged by the respective ratchet wheels 52, the said lugs being held against the ratchet wheels by means of the springs 57 mounted in the spring supporting bracket 58 secured to the bed of the machine. Integrally or otherwise connected with the arms 55 of the hammer levers 53 are the substantially vertical arms 59 the upper ends of which overhang the counter shaft 8 and are provided with adjustable hammer screws 60 which engage the shaft to transmit the blows thereto. As the drive shaft 5 is rotated the teeth of the respective ratchet wheels 52 slip over the lugs 56 on the respective hammer levers and force the same downwardly which raises the hammer screws 60 from the shaft 8. As each tooth of the respective ratchet wheels passes by the lugs 56 the springs 57 snap the hammer lever arms 55 upwardly so as to cause the hammer screws 60 to successively strike the counter shaft 8 and impart blows thereto, the staggered relation of the teeth of the ratchet wheels causing the hammer screws to alternately strike the shaft 8 in rapid succession. The force of the blows of the hammer levers may be varied by adjusting the tension of the spring by means of the rods 57. The counter shaft 8 projecting forwardly from the extension shaft 130

bearing 4 is allowed to spring or vibrate a limited amount in order to transmit the force of the blows of the hammer screws to the piston ring being operated upon, and as 5 the drive shaft 5 and counter shaft 8 rotate simultaneously and for the same length of time the piston ring will have the indentations rolled and hammered thereinto simultaneously. While the forward end of the 10 shaft 8 may vibrate and spring under the blows from the hammer levers, the bearing bracket 16 prevents the shaft from bending upwardly or breaking under the pressure incident to the operation of the die member 15 against the piston ring and anvil 18.

With my improved method of densifying piston rings by rolling, it will be noted that the indentations in the ring can be accurately and uniformly produced in a very simple 20 and inexpensive manner. The rolling of the piston ring by my new process and machine produces a uniform tension in the ring, which has heretofore been impossible due to the difficulty in either uniformly spacing the 25 indentations in the ring or producing blows of uniform intensity. In the modern machines for hammering piston rings the ring is usually fitted within a die and the expansion thereof caused by the hammering is 30 limited by the walls of the die whereas in my present apparatus the ring is free to expand in all directions and uniformly while being operated upon by the die member 11 upon the anvil 18. The piston ring is rotated and advanced under the die member 35 automatically and by the die member itself so that the indentations are properly spaced thereby eliminating the usual complicated and unreliable mechanism for simultaneously 40 forming the indentations and rotating the piston ring.

It will be understood that the projections 13 on the die member for forming the indentations in the piston ring may be of any suitable or desirable configuration and of any 45 size and that the size of the die member 11 can be varied according to the diameter of the piston ring being operated upon. The densification of the ring may be accomplished by varied spacing of the indentations with blows or pressure of uniform intensity, or the indentations may be spaced equidistantly and formed by varying pressure or 50 blows of varying intensity. It will also be observed that in some cases it may be desirable to form the indentations in the piston ring by rolling only, and when such is the case the hammer levers 53 can be removed from the machine or the hammer screws 60 can be so adjusted as to prevent contact thereof with the counter shaft 8. The anvil 65 might also be the driven member for rotating the piston ring instead of the die member being driven as shown in the drawings, and the die member could be yieldingly mounted

with respect to a fixed anvil instead of the anvil being yieldingly mounted with respect to a fixed die member as shown. It will thus be seen that many modifications and changes can be made in the detail construction and arrangement of the parts of my machine without departing from the spirit or scope of the invention, and I do not desire to be limited in the construction and use of my invention except as required by the following claims when construed in the light of the prior art.

Having thus described the invention, what I claim is:

1. The method of densifying packing rings consisting in simultaneously rolling and hammering a packing ring.

2. The method of densifying packing rings consisting in simultaneously hammering and rolling indentations into a surface 85 of the ring.

3. The method of densifying packing rings consisting in passing a ring between a pair of opposed members, one of which is a rotating die member, and exerting blows 90 upon one of said members simultaneously with the rotation of said die member.

4. The method of densifying packing rings consisting in forming the periphery of a die member with a plurality of projections, placing a ring between said die member and another member, maintaining engagement of said die member and said second-mentioned member with said ring, rotating one of said members to rotate said 100 ring, and exerting blows on one of said members simultaneously with said rotation.

5. In a machine of the character described, the combination of a rotatable die member, an anvil member arranged in 105 opposed relation to said die member and movable in a plane at right angles to the plane of rotation of said die member, said die member and anvil member being adapted to receive a packing ring 110 between them, means for yieldingly maintaining engagement of said die member and said anvil member, and means for moving one of said members to rotate said ring between them.

6. In a device of the character described, the combination of an anvil to support a packing ring, and means for simultaneously rolling and hammering indentations into a surface of said ring.

7. In a device of the character described, the combination of a die member, an anvil to support a packing ring between itself and said die member, and means for simultaneously rotating said die member and exerting blows thereon.

8. In a device of the character described, the combination of a die member, an anvil to support a packing ring between itself and said die member, and means for simul- 130

aneously causing relative movement of said die member and said packing ring and exerting blows upon said die member.

9. In a device of the character described, 5 the combination of a die member, an anvil to support a packing ring between itself and said die member, means for holding said packing ring between said die member and said anvil under pressure, means for 10 causing relative movement of said die member and said packing ring, and means for exerting blows upon said die member simultaneously with said relative movement of the die member and packing ring.
- 15 10. In a machine of the character described, the combination of a rotatable die member, means for yieldingly maintaining frictional engagement between said die member and said ring, means for producing relative movement of said die member and said ring, and means for exerting blows on said die member simultaneously with said relative movement of said packing ring and said die member.
- 20 11. In a machine of the character described, the combination of a rotatable die member, an anvil member arranged in opposed relation to said die member to receive a packing ring between itself and said die member, means for producing relative movement of said anvil and said die member to rotate the said ring therebetween, means for yieldingly holding said die member and said anvil member in frictional engagement with 30 said ring, and means for exerting blows on one of said members simultaneously with the relative movement thereof.
- 25 12. In a machine of the character described, the combination of a rotatable die member, an anvil member arranged in opposed relation to said die member and movable in a plane at right angles to the plane of rotation of said die member, said die member and anvil member being adapted to receive a packing ring between them, means for yieldingly maintaining engagement of said die member and said anvil member, means for moving one of said members to rotate said ring between them, and means 45 for exerting blows on one of said members simultaneously with the rotation of said ring.
- 30 13. In a device of the character described, the combination of a shaft, a die member mounted thereon, an anvil to support a packing ring between itself and said die member, means for causing relative move- 40 ment of said die member and said packing ring, and means for imparting blows to said shaft simultaneously with said movement.
14. In a device of the character described, the combination of a shaft, means for rotating the same, a die member fixed on said shaft, an anvil to support a packing ring 45 between itself and said die member, and means for imparting blows to said shaft simultaneously with the rotation thereof.
15. In a device of the character described, the combination of a bearing, a shaft journaled therein and projecting a substantial distance outwardly from said bearing, a die member mounted on said outwardly projecting portion of the shaft, an anvil to support a packing ring between itself and 50 said die member, and means for imparting blows to said projecting portion of the shaft, said blows being transmitted to the die member by the vibration of said projecting portion of the shaft.
16. In a device of the character described, the combination of a rotatable die member, and an anvil having a movable portion for supporting a packing ring between itself and said die member, said packing ring being 55 rotated by engagement with said die member and said movable portion of the anvil moving beneath said ring by frictional engagement.
17. In a machine of the character described, the combination of a rotatable die member, a support for a packing ring in opposed relation to said die member to receive a packing ring between itself and said die member, means for rotating said die member to rotate said ring, and means for automatically stopping rotation of said die member at the end of one revolution.
18. In a machine of the character described, the combination of a rotatable die member, a support for a packing ring in opposed relation to said die member to receive a packing ring between itself and said die member, a source of power, a driving mechanism for connecting said source of power 105 with said die member to rotate the latter, means for automatically disconnecting said source of power from said die member after one revolution of said die member, and automatic brake means for overcoming the momentum of said driving mechanism simultaneously with said disconnecting of the source of power from said die member.

JACOB B. WENZEL.
